UNITED STATES PATENT OFFICE

2,452,426

HOLDER FOR SHEET MATERIAL

Edward C. Blaske, Wellsville, N. Y.

Application December 6, 1946, Serial No. 714,606

4 Claims. (Cl. 164—79)

1

This invention relates to new and useful improvements and structural refinements in holders for sheet material, more specifically, material such as insulating board panels, insulated brick siding, or the like, and the principal object of the invention is to provide a device of the character herein described whereby such material in either sheet or strip form may be firmly and securely held while it is being marked or cut.

A further object of the invention is to provide a holder which will accommodate strips or sheets of various sizes and with the assistance of which the measuring and cutting operation may be easily and accurately performed.

Another object of the invention is to provide a holder which is simple in construction and which will not easily become damaged.

An additional object of the invention is to provide a holder which may be conveniently transported and which will readily lend itself to economical manufacture.

With the above more important objects in view and such other objects as may become apparent as this specification proceeds, the invention consists essentially of the construction and arrangement of parts as shown in the accompanying drawings in which:

Figure 1 is a top plan view of the invention;

Figure 2 is a front view thereof;

Figure 3 is a cross sectional view, taken substantially in the plane of the line 3—3 in Figure 1;

Figure 4 is a fragmentary cross sectional detail showing one of the locking cams used in the invention;

Figure 5 is an underside plan view of the cam shown in Figure 4, but illustrating the same removed from the structure in which it is mounted;

Figure 6 is an elevational view of the device shown in Figure 5;

Figure 7 is a cross sectional view, taken substantially in the plane of the line 7—7 in Figure 1;

Figure 8 is a perspective view of a gauging member used in the invention, and

Figure 9 is a cross sectional view, taken substantially in the plane of the line 9—9 in Figure 1.

Like characters of reference are used to designate like parts in the specification and throughout the several views.

Referring now to the accompanying drawings in detail, the invention consists of a holder designated generally by the reference character 10, the same embodying in its construction a flat platform or bed 11 supported in elevated position

2

by a pair of rails 12 which are secured to the under side of the bed, as is best shown in Figure 7.

A pair of parallel guides 13 are secured at the side edges 14 of the bed 11, the inner, that is, the opposed faces of the guides being formed with longitudinally extending grooves or channels 15.

A substantially U-shaped gauging member 16 is slidable on the bed 11 between the guides 13, the side arms 17 of the member 16 being provided with laterally projecting rails 18 which slidably engage the channels 15, as will be clearly apparent.

The side arms 17 of the member 16 are secured to the mid-portion 19 of the member in any suitable manner and a pair of braces 20 are also provided to reinforce the member structure. It will be observed that by simply sliding the member 16 between the guides 13 as indicated by the arrows 21, the distance of the member portion 19 with respect to the front edge 22 of the bed 11 may be readily varied.

The member 16 may be releasably locked in any desired position by a pair of locking cams 23, each of which is rotatably positioned in a recess 24 formed in the forward end portions of the side arms 17. Each of the cams 23 may be actuated by means of a handle 25 formed integrally with the boss 26 which is also provided with a shank 27.

As is best shown in the accompanying Figures 4 and 6, the shank 27 includes a cylindrical portion which is rotatable in a bore 28 provided in each of the side arms 17, while the cam 23 is mounted upon a square portion 29 of the shank, where it is retained by means of a suitable nut 30.

The cams 23 are disposed in alignment with the channels 15 of the guides 13 and it will be understood that by simply actuating the handle 25, the cams will be brought in frictional engagement with the grooves 15 and the member 16 will be releasably retained or locked in position. It should be added that the continuity of the rails 18 is interrupted as at 31, so as to accommodate the cams 23, as is best shown in Figure 8.

A clamping strip 32 is attached at one end thereof to one of the guides 13 by means of a hinge 33, while the remaining end of the strip is equipped with a tubular socket 34 accommodating a slidable locking bolt 35. This locking bolt is receivable in an eye or socket 36 secured to the remaining of the guides 13, as will be clearly apparent.

Finally, it will be observed that either one or both of the guides 13 are inscribed with a grad-

uated scale 37, the zero line of the scale coinciding with the front edge 22 of the bed 11.

When the invention is placed in use, a strip or sheet of material 38 is positioned on the bed 11 so that one edge 39 thereof contacts the gauging member 16. The locking cams 23 may then be loosened and the gauging member may be adjusted with respect to the scale 37 so that the distance between the forward edge 40 of the gauging member and the edge 22 of the bed is equal to the length or width of the material desired.

The locking cams 23 should then be retightened and the clamping strip 32 (which heretofore has been in an open position) should be lowered so as to press upon and firmly hold the material to be cut. The cutting operation may be undertaken by simply using the edge 22 of the bed as a guide for the cutting instrument.

The locking bolt 35 and the co-acting eye 36 serve to retain the clamping strip 32 in the closed position, as will be clearly understood.

It is believed that the advantages and use of the invention will be clearly apparent from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A holder for sheet material, comprising in combination, a flat bed, a pair of parallel guides provided at the side edges of said bed, a substantially U-shaped gauging member slidable in said guides, releasable means for locking said member, a material clamping strip hinged at one end thereof to one of said guides, a locking bolt at the remaining end of said strip, and an eye on the remaining of said guides, said bolt being engageable with said eye.

2. The device as defined in claim 1, in which said means for locking said member comprises a pair of cams provided on said member, said cams being frictionally engageable with said guides.

5. 3. A holder for sheet material comprising in combination, a flat, elevated bed, a pair of parallel guides secured at the side edges of said bed, the opposed faces of said guides being formed with a pair of longitudinally extending channels, 10 a substantially U-shaped gauging member slideable between said guides and engaging said channels, a locking cam provided at each end of said member and adapted to releasably engage said guides, and a clamping strip associated with 15 said guides, said strip being adapted to releasably retain the material on said bed.

4. A holder for sheet material comprising in combination, a flat, elevated bed, a pair of parallel guides secured at the side edges of said bed, 20 the opposed faces of said guides being formed with a pair of longitudinally extending channels, a substantially U-shaped gauging member slideable between said guides, the side arms of said member engaging said channels, a pair of locking cams rotatably mounted in said side arms and adapted to releasably engage said guides, externally operable means for actuating said cams, 25 a clamping strip hingedly connected at one end thereof to one of said guides, a slideable lock bolt at the remaining end of said strip, and an eye provided on the remaining guide, said bolt being engageable with said eye.

EDWARD C. BLASKE.
